CLAIM

The ornamental design for a light module, as shown and described.

DESCRIPTION

FIG. 1 is a top perspective view of a light module showing my new design.

FIG. 2 is a bottom perspective view thereof.

FIG. 3 is a right side view thereof.

FIG. 4 is a left side view thereof.

FIG. 5 is a front view thereof.

FIG. 6 is a rear view thereof.

FIG. 7 is a top plan view thereof; and,

FIG. 8 is a bottom plan view thereof.

The broken lines shown in the figures depict portions of the light module that form no part of the claimed design.

1 Claim, 8 Drawing Sheets

FIG. 2
